UNITED STATES PATENT OFFICE

ARCHIE REXALD WOLFE, OF SUMMIT, NEW JERSEY

CAM LOCK CONTRACTION SOCKET

Application filed March 6, 1929. Serial No. 344,888.

(GRANTED UNDER THE ACT OF MARCH 3, 1883, AS AMENDED APRIL 30, 1928; 370 O. G. 757)

My invention relates to improvements in electric light sockets adapted to receive and engage the standard screw rim plug or lamp, and the objects of my improvements are, 5 first, to produce an electric socket into which the standard screw rim electric plug or lamp can be quickly inserted, supported and electrically connected thereto without screwing, and from which said plug or lamp can be 10 quickly removed therefrom without screwing, thus saving the American public millions of dollars worth of time each year that is now wasted while screwing the standard screw rim plug or lamp into the standard 15 screw rim socket; second, to provide in a contraction socket a switch actuated by spring force for simultaneously elevating the center contact of said socket and completing the electrical circuit through said socket, and 20 for simultaneously depressing said center contact and breaking said electrical circuit, and means for operating said switch on the outside of said socket; third, to produce in a contraction socket a switch of low cost manu- 25 facture readily designed to be used in the standard screw rim socket and electric light sockets in general, and for all electrical switching purposes requiring spring action make and break of electric currents; fourth, 30 to provide in a cam lock contraction socket a simply constructed, spring actuated, eccentric cam lock for cotterizing or locking the screw rim of the standard screw rim plug or lamp within the rim of said socket, provi- 35 sion for quickly unlocking same and provision for operating said eccentric cam lock on the outside of said socket; fifth, to provide in a cam lock contraction socket a spring actuated, eccentric cam lock, which with 40 slight change in design is readily adapted to be used for expansion purposes in electric expansion plugs for locking the latter within the screw rim of the standard screw rim socket. 45 One form of my invention is illustrated in the accompanying drawings, in which, Fig. 1, is a view looking down on the top of the invention from a point vertically above its center; Fig. 2, is a vertical sectional view on the broken line 1 1, Fig. 1; Fig. 3, is a verti-

cal sectional view on the broken line 2 2, Fig. 1; Fig. 3a is a sectional view showing the switch in its off position; Fig. 4 is a view of the bottom of the invention; Fig. 4a is a perspective view of the annular ring used in 55 my invention; Fig. 5, is a view of a part of the invention showing the top of the lower section of the insulation body with all mechanism removed excepting the metal fulcrum bearing for the contactor and the bolt securing 60 said bearing; Fig. 6, is a view of a part of the invention showing the reciprocating control bar of said socket switch; and Fig. 7, is a perspective view of a part of the invention showing the power and fulcrum end of 65 the switch contactor.

Similar numerals refer to similar parts throughout the several views.

The metal threaded bolts 1, and 2, pass through apertures provided in and clamp together the metal shell 5, annular member or ring 6, upper section 7, of the insulation body and lower section 8, of the insulation body. The nuts 3, and 4, secure said bolts 1, and 2, respectively, and are countersunk into the 75 bottom of said section 8.

The shell 5, is provided with a threaded sector 9, the flanged camshaft bearing 10, the slotted camshaft brace bearing 11, and the cam aperture 12. 80

The cam 13, is secured eccentric to the camshaft 14, and two-thirds of the circumference of the former is threaded to mesh with the threads on the screw rim of the standard screw rim plug or lamp. Said 85 camshaft 14, is rotatable and supported in the bearing 10, and slotted bearing 11, in said shell 5, and the bearing 15, in said annular ring 6.

The flange 16, which is secured to said camshaft 14, prevents downward movement of the latter when rotatated by the insulated handle 17, which is keyed to said camshaft 14, and secured by the threaded nut 18. The spiral spring 19, encircles camshaft 14, and its upper end is secured to a projection of said annular ring 6, and the lower end to said handle 17, thus tending to keep said camshaft 14, and cam 13, in the locked position as shown in Fig. 2. And a ninety degree ro- 90 95 100

tation of said camshaft 14, against the tension of said spring 19, by means of said handle 17, moves said cam 13, to the unlocked position.

6 The cavity 20, in said sections 7, and 8, accommodates the lower end of said camshaft 14, spring 19, handle 17, and nut 18.

10 Said shell 5, being in permanent electrical contact with annular ring 6, electric current from the former is conducted direct to a downward projection of the latter which forms the shell terminal post 21, of said socket.

15 The switch control bar 22, is adapted to be manually reciprocated a limited distance in the switch cavity 23, in the upper end of section 8, and is provided with the insulated handles 24, and 25, the vertical stops 26, at one end, and the horizontal stops 27, at the other end. The latter project into the horizontal channels 28, near the bottom of the cavity 23, thus preventing excess vertical motion of said bar 22, when said socket is assembled.

20 The metal spring cam 29, is rigidly secured to said bar 22, and when the latter is moved in the "on" position of said switch as shown in Figs. 1, 2, 3, and 4, said spring cam 29, acting on the power end 30 of the metal triple ended contactor 31, moves the latter so that its 25 weight end 32, presses on and makes electrical contact with the lower arm of the L-shaped, metal center contact 33, and as the latter passes through and is pivoted at its apex to said insulation section 7, its upper 30 arm is automatically elevated until said lower arm is stopped by said section 7. Reciprocation of the bar 22 to the "off" position moves the spring cam 29 so that the power end 30 of contactor 31 will ride over the raised 35 portion 43 of the spring cam, as shown in Figure 3a. This forces the end 32 of the contactor 31 away from the center contact 33, breaking the electrical circuit and permitting the contact 33 to assume the position shown 40 in Figure 3a. When in either the "on" or "off" position of the switch, the cam spring 29 securely holds the contactor 31 in place preventing undesired movement of the member 29. The fulcrum end 34, of said contactor 31, is pivoted or hinged to the metal 45 fulcrum 35, which is secured to the under side of said section 7, by the threaded metal screw 36, which passes through an aperture provided in section 8, and engages a threaded 50 aperture in the metal center contact terminal post 37, securing the latter within a cavity provided in the lower end of said section 8. The shoulders 38, and 39, of said fulcrum end 34, bear on and make electrical contact with 55 said fulcrum 35. And the bearing tip 40, of said fulcrum end 34, is retained in the aperture 41, Figure 5, of said fulcrum 35, by means of the tip flange 42.

60 The circuit for the above socket is from binding post 37, through screw 36, fulcrum

35, contactor 31, center contact 33, filament of lamp, shell 5, annular ring 6, and binding post 21.

65 In the practical operation of the contraction socket described herein, the switch should first be placed in the off position. The handle 17, is then placed in the off position and held there until a standard screw rim plug or lamp is fully inserted within said socket. Handle 17, is then released, 70 after which said switch may be moved in the on or off position as desired, the former position completes the electrical circuit through said socket and the off position opens said circuit. 75

80 The invention described herein may be manufactured and used by or for the Government of the United States for governmental purposes without the payment to me of any royalty thereon. 85

I claim:

1. In a contraction socket comprising an insulation body, a movable center contact mounted on said body, an elevating and depressing means within said body for elevating and depressing said center contact, and a means on the outside of said body for operating said elevating and depressing means. 90

2. In a contraction socket comprising an insulator body, a movable center contact mounted upon said body, a terminal post mounted upon said body for said center contact, a switch means within said body for simultaneously elevating said center contact and completing electrical contact between the latter and said terminal post and for simultaneously releasing said center contact and breaking said electrical contact, and a means on the outside of said body for operating said switch means. 95

3. In a contraction socket, a metal shell mounted upon an insulation body and adapted to receive the screw rim of a standard screw rim plug or lamp without screwing the latter, a movable metal center contact mounted upon said insulation body, a terminal post mounted upon said body for said center contact, a cam means on said metal shell for engaging and releasing said screw rim without screwing the latter, a switch means within said body for simultaneously elevating said center contact and completing electrical contact between the latter and said terminal post and for simultaneously releasing said center contact and breaking said electrical contact, a means on the outside of said body for operating said cam means, and a means on the outside of said body for operating said switch means. 110

4. In a contraction socket comprising an upper section insulation body and a lower section insulation body, an annular ring mounted upon said upper section, a metal shell mounted upon said ring and adapted to receive the screw rim of a standard screw 115

rim plug or lamp without screwing the latter, a terminal post upon said ring for said shell, a sector upon said shell threaded to mesh with the threads upon said screw rim, a cam means 5 upon said shell for engaging and releasing said screw rim without screwing the latter and comprising a cam threaded to mesh with the threads on said screw rim and affixed eccentric to a rotary shaft projecting downward within said upper and lower sections, bearings upon said shell for said shaft, a bearing upon said ring for said shaft, a spring for actuating said shaft and cam in the position to engage said screw rim, and an 10 insulated handle affixed to said shaft and projecting on the outside of said body sections for rotating said shaft and cam in the position to release said screw rim and against the tension of said spring.

20 5. In a contraction socket comprising an upper and lower section insulation body, a movable metal center contact mounted upon said upper section, a terminal post mounted upon said lower section for said center contact, a switch means within said lower section for simultaneously elevating said center contact and completing electrical connection between the latter and said terminal post and for simultaneously releasing said center contact and breaking said electrical connection and comprising a metal fulcrum bearing electrically connected to said terminal post, a triple ended contactor with its fulcrum end pivoted to said bearing, a spring 25 cam affixed to a reciprocating control bar and engaging the power end of said contactor for actuating the weight end of said contactor into and out of engagement with said center contact, and insulated handles projecting on 30 the outside of said lower section and affixed to said control bar for reciprocating the latter.

35 6. An electric socket including a body member, a shell, an annular ring mounted between the body and shell, a terminal post extension formed on the ring, a cam mounted on the shell for securing a standard screw rim therein, operating means for the cam, a center electrical contact within the body, a 40 control switch for the center contact, and means for operating the switch.

45 ARCHIE REXALD WOLFE.
